UNITED STATES PATENT OFFICE

1,938,358

ELASTIC FLUID GENERATOR

Arthur R. Smith, Schenectady, N. Y., assignor to
General Electric Company, a corporation of
New York

Application December 1, 1932. Serial No. 645,264

1 Claim. (Cl. 122—6)

The present invention relates to elastic fluid generators, more particularly to the type of generators which comprises a plurality of tubes, conduits or like heating elements lining the wall or 5 walls of a furnace for heating and evaporating liquid passed through the tubes.

Heat is transmitted to the heating elements by radiation and conduction. To prevent excessive temperatures of the furnace wall or walls the 10 heating elements are spaced somewhat from these walls. It is also necessary to provide clearance between the adjacent heating elements for permitting relative sidewise expansion between adjacent elements. These clearances, however, permit ashes and slag to enter the space defined 15 between the heating elements and the furnace wall.

The object of the present invention is to provide an improved construction and arrangement 20 of heating elements in an elastic fluid generator of the type above specified in which the amount of slag and ashes entering the space between the heating elements and the furnace wall through the gaps between adjacent heating elements is considerably minimized.

For a consideration of what I consider to be 25 novel and my invention, attention is directed to the following description and the claim appended thereto in connection with the accompanying drawing.

In the drawing, Fig. 1 represents a cross section through a plurality of heating elements constructed and arranged in an elastic fluid generator 30 in accordance with my invention; Fig. 2 is a front view of Fig. 1; Fig. 3 illustrates the heating elements together with a portion of the furnace wall; and Fig. 4 illustrates a modification according to my invention.

Referring to Figs. 1 to 3, a plurality of heating 40 elements 10, 11, 12 are provided adjacent each other, lining a furnace wall 13 and defining a space 14 therewith. The heating elements are of the type which may be advantageously used in connection with mercury boilers as shown in the copending application of A. J. Nerad, Serial 45 No. 628,519, filed August 12, 1932. Each heating element comprises an outer shell 15 of corrugated sheet metal and a plurality of heating tubes or pipes 16. In the present instance I have shown 50 three heating tubes for each element. The end portions of the tubes of each element are united to a single tube 17 as indicated in Fig. 3. The space defined between the tubes and the outer shell is filled with a substance 18 of high heat 55 conductivity such as copper. Heat is transmitted to the corrugated portion from any suitable source of heat by radiation and conduction. These heating elements are described more in detail in the Patent No. 1,866,367 to Nerad. Adjacent heating elements 10, 11, 12 are spaced from

each other, thus defining gaps 19, 20 respectively between them for permitting sidewise expansion of the elements. To minimize the amount of slag and ashes which may enter the space 14 through these gaps, means are provided in accordance 65 with my invention for sealing the gaps and at the same time permitting relative sidewise expansion between adjacent heating elements.

In accordance with the embodiment shown in Fig. 1, I unite a member 21 with one end portion of each shell. These members 21 form in substance extensions of one end of each shell, the end being bent at a right angle to the adjacent portion of the shell and slidably engages or overlaps the rear portion of the adjacent heating 75 element.

Whereas in Fig. 1 each element has an outer shell provided with a sealing extension at one end of the shell, I provide in accordance with the embodiment of Fig. 4 alternately heating 80 elements 25 and heating elements 26. The heating elements 25 have outer shells provided with extensions 27 at both ends of the shell and heating elements 26 have outer shells without such extensions.

With my invention I have accomplished a simple and reliable construction and arrangement for 85 heating elements in elastic fluid generators such as may be used for producing mercury vapor. The clogging of the space defined between the heating elements and the furnace wall is effectively prevented.

Having described my invention, together with the apparatus which I now consider to represent the best embodiment thereof, I desire to have it understood that the apparatus shown is only illustrative and that the invention may be carried out by other means.

What I claim as new and desire to secure by Letters Patent of the United States, is,—

In an elastic fluid generator, the combination of 100 a furnace wall, a plurality of fluid heating elements lining the wall, each element comprising an outer shell, a plurality of tubes for containing fluid spaced within the shell and filling material 105 of high heat-conductivity in the space defined between the shell and the tubes, the shell comprising a single trough-shaped, corrugated sheet of metal having a bent edge portion overlapping an edge of the shell of an adjacent element for preventing slag entering the space between the 110 elements and the furnace wall.

ARTHUR R. SMITH.
